LOCOMOTIVE STRUCTURE

**Karl S. Howard, Philadelphia, Pa., assignor to
General Steel Castings Corporation, Granite
City, Ill., a corporation of Delaware**

Application March 16, 1932. Serial No. 599,291

4 Claims. (Cl. 122—462)

This invention relates to railway rolling stock and consists particularly in a novel construction and arrangement of a locomotive smokebox and superheater.

It has been the usual practice in the construction of locomotive superheaters to utilize a single superheater header for both saturated and superheated steam, the header being located in the upper part of the smokebox and the superheater units extending downwardly therefrom and including portions extending into the superheater flues. Live steam is led downwardly from the header on each side of the smokebox to the valve chambers.

The main objects of the present invention are to simplify super heater construction and provide for a more direct flow of steam to the valve chambers than is obtained in previous designs.

Another object is to provide a superheater header structure which will serve as a brace for the smokebox wall.

These objects and others are attained substantially by the provision of separate saturated steam and superheated steam headers located in the upper and lower portions of the smokebox, respectively, and extending across the same.

In the accompanying drawings which illustrate the invention—

Figure 1 is a half front elevation of a smokebox embodying the invention and half vertical transverse section taken on line 1—1 of Figure 2.

Figure 2 is a side elevation of the structure in the smoke box with some parts sectioned for clearer illustration.

Figure 3 is a detail top view showing the upper or saturated steam header.

Figures 4 and 5 are detail vertical sections taken on the corresponding section lines of Figure 3.

Figure 6 is a detail top view showing the lower or superheated steam header.

Figures 7 and 8 are vertical sections taken on corresponding section lines of Figure 6.

Figure 9 is a view of a modified form of the invention, the right half being in elevation and the left half being taken on the line 9—9 of Figure 10.

Figure 10 is a vertical longitudinal section taken on the line 10—10 of Figure 9.

Figures 11 and 12 are detail vertical transverse sections taken on the corresponding section lines of Figure 10.

In Figures 1 to 8 is illustrated a locomotive boiler 1 mounting on the front end thereof the usual smokebox 2 including smokestack 3 and

lift pipe 4, deflector 6 and screens 5, exhaust pipe 7, and front flue sheet 9 to which are attached the forward ends of superheater flues 10. The smokebox is supported on saddle 11 having interior exhaust passages 12 and an inside live steam passage 13 at one side thereof. The cylinders and valve chambers (not shown) may be formed integral with the saddle. My copending application Serial No. 533,325 filed April 27, 1931 illustrates a similar cylinder saddle structure which also includes a throttle valve housing.

A saturated steam header 14 is mounted in the upper part of the smokebox upon brackets 15 and comprises a plurality of horizontally disposed chambers 16 and a transverse passage 17 extending along the rear side of the header and connected with the chambers 16. A central upwardly disposed passage 18 connects with tube sheet ring 19 and dry pipe 20.

A separate superheated steam header 21, mounted in the lower part of the smokebox on brackets 22, has a series of horizontally disposed chambers 23, corresponding with chambers 16 in the upper header, and a passage 24 extending transversely across the front side thereof and connected with chambers 23. A central opening 25 in passage 24 connects with a second passage 26 having an outlet 27 connecting with live steam pipe 28, the latter leading into passage 13 in the cylinder saddle. Outlet 27 and live steam pipe 28 are spaced transversely of the longitudinal center line of the locomotive in order to clear exhaust nozzle 7.

The lower surface of the upper header 14 and the upper surface of the lower header 21 are provided with rows of sockets or seats 29 and 46 for cooperating with ball joint elements 30 and 45 on the ends of superheater units 31 and 44, respectively. Each unit comprises an upturned inlet section of tubing connecting with the upper header 14, a horizontal portion extending back and forth within one of the boiler flues 10, and a downwardly disposed outlet section leading into the lower header 21.

It will be observed from Figures 1 and 2 that each row of ball joint seats 29 and 46 is associated with superheater units utilizing boiler flues in a column substantially in vertical alignment with that row. Consequently, all of the upturned ends of the units in each column are in substantially the same vertical plane and the downwardly disposed ends thereof are in a vertical plane spaced from the first vertical plane. The flow of steam from the saturated steam header 14 through the boiler flues and super-

heated steam header 21 to the cylinders is thus more direct than is the case where a single header is used for saturated and superheated steam and steam is led from the superheater 5 flues upwardly to the single header and then down to the cylinders.

The superheater units are secured to both headers by means of T-head bolts 33, which pass through slots 34 separating the compartments of the headers, and clamps 32 each engaging corresponding ends of a pair of units in adjacent columns. The bolt heads are lodged between ridges 35 extending along slots 34 on the opposite surfaces of the headers.

15 The throttle valve (not shown) may be mounted in the cylinder saddle, as in the above mentioned copending application, or in the live steam pipe 28, or in the steam dome. Various other locomotive fittings may be mounted in the smokebox if desired.

20 In Figures 9 to 12, the upper and lower headers 36 and 37 are cast integral with the smokebox and serve to brace the wall 40 thereof. The longitudinal walls of the headers merge with the 25 main side wall of the smoke box and cooperate with the latter in forming the end chambers in the headers. This gives a longer header and more steam-receiving chambers and provides a greater surface exposed to the flue gases in the 30 smoke box. Reinforcing ribs 38 and 39 are provided at the intersections of the header structures with the smokebox wall and longitudinal ribs 41 assist in bracing the upper header. Immediately above the upper header the smoke box 35 wall is provided with vertical portions 43 forming a rectangular opening to permit access to the headers. The arrangement of the superheater piping and various details in this form is the same as in the form previously described.

40 It will be noticed that superheated steam passing from the flues through the downwardly extending portions of the superheater tubes to the lower header and thence through the inside 45 live steam pipe to a connection in the cylinder saddle is at all times in the hottest part of the smokebox, that is, directly in the path of hot

50 steam. This is important, as it insures that the superheated steam will be at its maximum temperature when it reaches the cylinder saddle. The superheater 55

60 steam is heated in the flues by the flue gases

65 passing from the flues through the smokebox to the stack.

70 The superheater units are secured to both

75 headers by means of T-head bolts 33, which

80 pass through slots 34 separating the compartments of the headers, and clamps 32 each

85 engaging corresponding ends of a pair of units in adjacent columns. The bolt heads are

90 lodged between ridges 35 extending along slots 34 on the opposite surfaces of the headers.

gases passing from the flues through the smokebox to the stack. Consequently, the live steam is maintained at a higher temperature and the operation of the locomotive is accordingly more efficient and economical than where the present types of superheater headers are used.

95 Obviously the invention is not limited to the exact details of structure illustrated in the drawings and these may be modified in various ways without departing from the spirit of the invention and the exclusive use of all such modifications as come within the scope of the appended claims is contemplated.

What is claimed is:

1. A one piece locomotive smokebox having a 90 transversely extending steam header formed integral therewith, the longitudinal walls of said header forming braces for said smokebox and the main wall of said smoke box forming the ends of steam receiving chambers of said header.

95 2. As a new article of manufacture, a one piece steam header comprising a series of steam compartments, a steam passageway connected to said compartments and having a centrally located outlet, and another steam passageway connected 100 to said outlet, said second mentioned passageway having an outlet spaced from said first mentioned outlet.

3. An integral locomotive smoke box structure having a plurality of vertically spaced steam 105 headers extending across and bracing the same, the longitudinal walls of said headers merging with the side wall of the smoke box to form therewith a steam receiving chamber.

4. An integral cast metal steam header having 110 a plurality of steam compartments and an off center steam outlet connection, and means for equalizing the flow of steam from said compartments through said connection and comprising a passage communicating with all of said compartments and having a central outlet and a second passage extending along said first-mentioned passage from said center outlet to said connection.
